Filed Jan. 21, 1963, Ser. No. 73,253

Term of patent 3½ years

(Cl. D34—5)

FIG. 4.

FIG. 1 is a top plan view of an amusement roundabout table showing my new design.

FIG. 2 is a side elevation thereof. The opposite side of the amusement roundabout table from that shown is the same in appearance as the side shown.

FIG. 3 is a rear elevation of the amusement roundabout table.

FIG. 4 is a bottom plan view of the amusement roundabout table.

I claim:

The ornamental design for an amusement roundabout table, as shown and described.
